10 Claims. (Cl. 19—245)

This invention relates to a textile handling arrangement, and more particularly to an improved apparatus for use in the drafting of a running length of textile fibers.

For a number of years in the textile industry, it has been the practice to employ roll-type drafting systems in which there are two, three, or more pairs of spaced-apart rolls driven at exceedingly faster rates along the flow path of the fiber mass passing therethrough in order to provide a desired degree of drafting of the fiber mass. However, due to the space limitations caused by required roll size, as well as other limitations, the spacing between the rolls has been such as to lose control of the fibers in the drafting zone between the succeeding rolls, and in order to overcome this difficulty, the industry has adopted generally the employment of a combined roll and apron-type drafting arrangement in which one or more aprons is employed for carrying and controlling the fiber mass to a point more close to the nip of a succeeding pair of rolls, particularly in such areas where high draft is to be achieved. However, while the conventional apron system does provide a material improvement and advantage in this respect, there is still a space left between the nose end of conventionally employed apron-drafting systems and the succeeding adjacent pair of nip rolls, with consequent loss of control of the fibers in this space. This may and commonly does result in the deterioration of quality of the resulting yarn formed from the fiber mass, as well as loss of fibers which may drop out from the fiber mass, including particularly short fibers, in this free uncontrolled zone between the rolls or between the nose end of the apron assembly and the succeeding rolls.

It is a major feature of the present invention to provide an improved arrangement in which support and guidance control is provided for the fibers along substantially the entire distance between two succeeding pairs of rolls, and particularly in the drafting zone immediately preceding the faster-driven rolls of two succeeding pairs of rolls.

A further feature is the cleaning of the bottom rolls of two succeeding pairs of rolls by a bridge device which serves also to support and guide the fiber mass between the two pairs of rolls.

Still a further feature is the provision of an improved, multiple function cradle assembly and bridge element subassembly which effects roll cleaning and improved fiber support and control between spaced drafting rolls, as well as apron cleaning and improved apron tracking, and cradle alignment.

According to the invention a multiple function fiber-supporting and guiding bridge element is disposed between and carried in rubbing engaging relation on the bottom rolls of two succeeding pairs of drafting rolls, being preferably incorporated in an improved cradle arrangement including an apron-supporting and guiding element connected to the bridge element. The novel bridge element serves two basic functions, one of which is the support and guiding control of the fibers between the respective succeeding pairs of rolls, particularly in the drafting zone immediately preceding the front rolls of the respective adjacent pairs of rolls, and the second basic function being the cleaning of the fiber carrying peripheral portion of the two bottom rolls on which the bridge element lies. Additionally, in the preferred embodiment

2

the bridge element serves to clean the exterior surface of the cooperating apron during the passage of the apron thereby along its fiber-control run. The apron is preferably guided about a combination roll-and-apron-cleaning and apron-positioning element disposed in guiding relation within the apron periphery and engaging in cleaning relation both the apron interior and the respective apron-carrying roll surface. Thus, there is effected in the preferred embodiment, cleaning of three rolls of two succeeding pairs of rolls, as well as cleaning of the apron interior and exterior, and improved guiding and support of the fiber mass along substantially the entire distance between the pairs of rolls, and particularly in the important drafting zone immediately preceding the faster-driven second of the two pairs of rolls. Also, in the preferred embodiment, the interfacing surfaces of the bridge element and the apron and roll-cleaning and guiding and controlling elements serve to aid in the guiding of the apron along its fiber-control run and the guiding and control of the fibers along this run.

Still other objects and attendant advantages will become apparent to those skilled in the art from a reading of the following detailed description of two physical embodiments constructed in accordance with this invention, taken in conjunction with the accompanying drawings wherein:

FIGURE 1 is a perspective view of a single drafting assembly incorporating one embodiment of the present invention.

FIGURE 2 is a longitudinal section view of the arrangement of FIGURE 1.

FIGURE 3 is an exploded view in perspective of the novel cradle arrangement of FIGURE 1.

FIGURE 4 is a longitudinal section view of a modified and preferred embodiment according to the invention.

FIGURE 5 is an exploded view of the preferred cradle assembly of FIGURE 4.

FIGURE 6 is an inverted view in perspective of the upper element of the cradle assembly of FIGURES 4 and 5.

Referring now to the figures of the drawings, in each of the embodiments the invention is shown as applied to a drafting system incorporating three parts of successively faster-driven drafting rolls, including back rolls 11, 13, middle rolls 15, 17, and front rolls 19, 21. Also, in each of the preferred embodiments, an apron is carried about the surface of roll 15 and is guided through a reduced radius nose zone adjacent roll 19 through the medium of a roll-and-apron-cleaning and apron-guiding element 25. The cleaning and guiding element 25 is connected to a multiple purpose bridge element 27 which extends between and rides, preferably in substantially floating relation, on the peripheral surface of each of preferably smooth-surfaced roll 17 and front roll 21. In the embodiment of FIGURES 1-3, the elements 25 and 27 are removably-connected together through the medium of two side spacer brackets 29 which are adjustably-secured to the respective cleaning-and-controlling elements 25, 27 through the medium of screws or studs 31, 33 engaging in adjustment slots 29a, 29b formed in the spacer bracket.

By adjustment of the bracket spacer element 29, the relative position of securing screw 33 in the slot 29b will determine the spacing between the adjacent interfacing apron-guiding surface 25c of element 25 and apron-and-fiber-guiding surface 27c of element 27. The slot 29a permits longitudinal adjustment of the element 25 with respect to the element 27, thereby permitting closer or further apart spacing of the roll 15 with respect to the roll 19. In operation, the element 25 may be either fixed in longitudinal position with respect to the element 27 or may be in floating longitudinal relation relative

thereto. This may be effected by either securing each of the screw elements 31 and spacer brackets 29 tightly against the side walls of the element 25 or by securing the screw element 31 lightly, though securely, so as to permit free movement of the screw along the slot 29a. In the latter instance a stud or bolt may preferably serve the purpose, whereas in the former longitudinally self-seating instance the employment of a common securing screw may be readily employed. It will be apparent, however, that while one mode of securing and spacing the elements apart is illustrated in this embodiment, there are various other ways of effecting this connection between the elements 25 and 27, either in fixed or adjustable relation with respect to one another.

Preferably, the apron-guiding element 25 is provided with means in the form of side shoulders 25d which extend about the opposite ends of the boss portion of the roll 15, in order to impart lateral stability to the assembly 25, 27, 29 with respect to the rolls 15, 17, and the passage of the fiber mass F therebetween. Lateral stability for the apron 23 is provided by the side spacer bracket elements 29.

Referring further to the apron-guiding element 25, this element has a roll-engaging concave cleaning surface 25a, an apron fiber-control-run-guiding surface 25c, a reduced diameter nose end 25b and a return surface 25f, thus guiding the apron in a tapered path extending from the roll 15 to and from a nose position adjacent the roll 19.

The cleaning and fiber control element 27 is, in this embodiment, illustrated as a block having two oppositely facing concave roll-engaging cleaning surfaces 27a, 27b, with an intermediate apron-engaging-and-guiding and fiber-mass-supporting-and-controlling surface 27c which extends from closely adjacent the roll 17 to the surface of front roll 21. The fiber-supporting-and-controlling surface 27c is preferably somewhat convex, as by forming thereon a chamfer or a long smooth convex curve at or closely adjacent the entrance end thereof, as indicated at 27f, in order to aid in feedthrough of the fiber mass between this surface and the adjacent fiber-control run of the apron 23. It is preferable that the curvature and positioning of the surface 27c, 27f and the adjacent interfacing surface 25b, be such that the apron-fiber-control run will be guided upwardly from the point of tangency between the rolls 15 and 17, when the fiber mass F is passing therebetween, as shown more particularly in FIGURE 2, in order to afford what has been found to be the best degree of control of the fibers in this zone.

As a further aid to the proper passage of the fiber mass F between the apron 23 and the fiber-supporting and controlling surface 27c of the element 27, there is preferably formed an undercut 27g at the entrance end of the concave surface 27a, thus providing a space of from approximately five to twenty-five thousandths inch depth and approximately one-eighth to one-quarter inch in length. This is of material value in preventing the protruding fibers in the fiber mass from being impinged between the roll periphery and the element thus causing the entire mass of fibers to follow thereabout as the fiber mass passes from between the nip formed between the apron and the roll 17. The apron 23 is itself of material importance in moving the fiber mass F past this critical zone and along the further control path extending between the apron and the surface 27f, 27c of the element 27.

It will thus be seen that the element 27 serves as a multiple-function element in which the concave surfaces 27a, 27b, not only stabilize the entire system 25, 27, 29, relative to rotation about the axis of either of rolls 15 or 17, but also serve to clean the rolls 17 and 21 through their rubbing engagement therewith, the element serving, through its fiber-supporting-and-control surface 27f, 27c, the additional and most vitally important function of supporting and controlling the passage of the fiber

mass F as it passes between the rolls 15 and 17 and the rolls 19, 21. Particularly, it will be noted that the element 27, through its extended surface 27c serves to support and control the path and passage of the fiber mass F in the important draft zone immediately preceding the nip of the rolls 19, 21.

In FIGURES 4-6, there is shown a preferred modification of the invention, incorporating elements 125 and 127 that correspond in function and mode of operation to elements 25 and 27 of the preceding described embodiment. In this embodiment, however, the elements are removably interconnected through the medium of side ears 129 formed on the element 125 and extending down about the side of the elements 127. The side ears 129 have detents 129a formed thereon which engage with pocket recesses 127i formed in the side walls of the center web portion of the cleaning and control element 127. While the detent and socket connection is shown with the detent 129a formed on the ears 129 and the socket recesses 127i formed on the element 127, it will, of course, be apparent that this may be reversed, and that other alternative methods of connection may also be employed, as for instance by passing a pin through the ears 129 and through a bore which may be formed in the element 127, or by employment of screws or other suitable connecting or securing means.

In the illustrated embodiment of FIGURES 4-6, the socket recesses 127i are preferably longitudinally elongated in a direction parallel to the surface 127c, so as to permit longitudinal self-adjustment of the element 125 with respect to the element 127, and thus permitting self-adjustment to accommodate varying tolerances between the rolls 15 and 19 or variations in diameter of the roll 15, or variations in setting between the rolls 15 and 19. Precisely complementary socket and recess connections may, however, of course be employed if desired and if no self-adjustment is necessary for a given instance of use.

The cleaning and controlling bridge element 127 in this embodiment has two cantilever legs 127m, 127n, which are connected by a central web section, and the entire element 127 may be formed of a material, such as Delrin, which is sufficiently elastic, though dimensionably stable, to permit the springing in of the legs 127m, 127n, for insertion and removal of the element 127 between the rolls 17 and 21. Thus, the insertion of this preferred element 127 differs from the insertion of the preceding described bridge element 27 in the embodiment of FIGURES 1-3 in that the bridge element 127 may be snapped into and out of position, whereas the element 27 must be inserted into position by first lowering such between the reduced diameter portions of the rolls 17 and 21 and then sliding such laterally sideways to a position engaging between the boss portions of the rolls 17 and 21. It will be apparent that the entire preferred embodiment of FIGURES 4-6 is more easily and quickly assembled and disassembled than the embodiment of FIGURES 1-3 illustrating the basic principles of the invention.

In other respects, the arrangement of FIGURES 4-6 is substantially identical to that of the first-described embodiment of FIGURES 1-3. Similar reference numerals are given to similarly functioning and shaped portions of the elements 125 and 127 as are given to the elements 25 and 27 of the preceding embodiment, with the corresponding portions of elements 125 and 127 numbered in the 125 and 127 series, whereas the preceding embodiment portions of the elements 25 and 27 are numbered in the 25 and 27 series.

While the invention has been described with respect to only two physical embodiments thereof, it will be apparent to those skilled in the art that various modifications and improvements thereof may be made without departing from the scope and spirit of the invention. For instance, the fiber control surface 27c or 127c of the element 27 or

127 may have formed thereon a tapered fiber-condensing groove, if desired. Further, the element 27 or 127 or both elements 25 or 125 and 27 or 127 may be laterally traversed transverse to the direction of the fiber flow path as by a traverse rod, if desired, rather than being maintained against substantial transverse lateral movement as in the two illustrated embodiments. Accordingly, it is to be understood that the invention is not to be limited by the particular illustrative and preferred embodiments disclosed herein, but only by the scope of the appended claims.

That which is claimed is:

1. A drafting assembly comprising two spaced-apart pairs of drafting rolls, an endless fiber-control apron disposed about one roll of one pair of said rolls and extending between said one roll and an adjacent roll of the other of said pair of rolls, means guiding said apron to form a nose end between said one roll and said adjacent roll, said apron having a fiber-controlling run extending between said one roll and said nose end thereof, said means guiding said apron including a portion in apron cleaning and supporting engagement with said fiber-controlling run, and a fiber-supporting-and-guiding bridge element extending between and engaging in supported relation to the respective surfaces of the other two of said pairs of rolls, said bridge element having oppositely extending concave roll-engaging surfaces formed at opposite ends thereof and being in floating supported relation on its respectively oppositely engaged rolls.

2. The structure of claim 1 including means supplying a fiber mass to be drafted between one of said spaced apart pairs of rolls, said bridge element being undercut adjacent the engaged roll of said pair of rolls being supplied said fiber mass to aid in feedthrough of said fiber mass between said bridge element and said apron, said undercut surface being slightly spaced from the surface of said engaged roll.

3. The structure of claim 1 wherein said bridge element has a fiber-supporting surface engaging with the exterior surface of said apron along the fiber-engaging run of said apron, means supplying a fiber mass to be drafted between one of said spaced apart pairs of rolls, and said fiber-supporting surface of said bridge element having an upwardly-inclined forward slope adjacent the engaged roll of said pair of spaced pair of rolls being supplied a fiber mass to aid in the feedthrough and control of said fiber mass.

4. Apparatus according to claim 1 wherein said bridge element has two resilient cantilever legs, one of said oppositely facing concave roll-engaging-and-cleaning surfaces being on each of said resilient cantilever legs.

5. A drafting assembly comprising two spaced-apart pairs of drafting rolls, an endless fiber control apron dis-

posed about one roll of one pair of said rolls and extending between said one roll and an adjacent roll of the other of said pair of rolls, an apron-cleaning-and-guiding-and-roll-cleaning element within the confines of said apron, a bridge element engaging in cleaning relation and therebetween the remaining two rolls of said pairs of rolls, and means connecting said elements together.

6. Apparatus according to claim 5 wherein each of said elements has a respectively interfacing spaced-apart apron-guiding surface formed thereon, means supplying a fiber mass to be drafted between each of said pairs of rolls, said apron-guiding surface on said bridge element engaging directly the fiber mass passing thereby and being in direct supporting and guiding relation thereto, said apron-guiding surface on the other of said elements engaging the interior surface of said apron passing thereabout and thereby indirectly guiding and aiding in the control of said mass of fibers.

7. Apparatus according to claim 5 wherein said connecting means includes side connecting spacers and means connecting said side spacers to said two elements, said side spacers having means thereon for varying the spacing between said elements and for longitudinal relative adjustment of said elements.

8. Apparatus according to claim 5 wherein one of said elements has formed on opposite sides thereof roll-engaging shoulders for lateral stabilization with respect to said rolls.

9. A drafting assembly comprising two spaced-apart pairs of drafting rolls, means supplying a mass of fibers between said drafting rolls in each pair, an element between said pairs of rolls having oppositely-facing concave surfaces, one of said concave surfaces engaging one of said rolls in one of said pairs of rolls, and the other of said concave surfaces engaging another of said rolls in the other of said pair of rolls, said element having a substantially planar surface supporting and guiding said fiber mass between said concave roll-engaging surfaces.

10. A textile fiber-controlling-and-roll-cleaning device comprising an element having two resilient legs, each of said resilient legs having a concave roll-engaging-and-cleaning surface facing in an opposite direction from the concave surface on the other leg, and a fiber-supporting-and-guiding surface extending between said concave roll-engaging-and-cleaning surfaces on said resilient legs.
